UNITED STATES PATENT OFFICE.

ALEXANDER CONSTANTINE IONIDES, JR., OF LONDON, ENGLAND.

AIR-GAS APPARATUS.

1,011,

Specification of Letters Patent.

Patented Dec. 19, 1911.

Application filed December 5, 1910. Serial No. 596,168.

To all who it may concern:

Be it known that I, ALEXANDER CONSTANTINE IONIDES, Jr., citizen of Great Britain, residing at 4 Porchester Terrace, London, W., England, have invented certain new and useful improvements in Air-Gas Apparatus, of which

the object of my invention is to provide means for extinguishing the back flash any time likely to occur with self supporting gas apparatus at ignition, and which is a source of danger, and to carry my invention into effect I construct my improved extinguisher as follows, reference being made to the accompanying drawing showing a front section and part elevation of my apparatus.

I make and form part of a delivery pipe B from supply, and that the part an pipe being cut off square, which blocks the enlargement with the space all around it, the section of the space around not being less than the area of the pipe, the action of the apparatus being to spread the gas in a thin layer instead of allowing it to form a solid mass it would if it were not inserted, and by have found that no back flash extinguisher, the reason being that the sudden spread out in the apparatus is immediately cooled below the temperature at which self supporting gas ignites and consequently any back flash is immediately extinguished the instant the

flame reaches the extinguisher. These extinguishers may be placed in any part of an air gas system where back flash is likely to take place, thus rendering any system perfectly safe in this respect.

Having now particularly described and ascertained the nature of my said invention and in what manner the same is to be performed I declare that what I claim is—

1. In a device for extinguishing the back flash in gas burning apparatus, the combination with the supply pipe having a portion intermediate its ends of greater diameter than the rest of the pipe, of an imperforate elongated baffle member in said enlargement, said baffle having a substantially flat face directed toward the burner and being of a diameter such that a space between its outer periphery and the inner periphery of the enlargement results, the sectional area of said space being not less than that of the supply pipe.

2. In a device for extinguishing the back flash in gas burning apparatus, the combination with the supply pipe having a portion thereof substantially cone shaped and of greater diameter than the rest of the pipe, of an imperforate substantially cone shaped baffle member in said enlargement the base of said member being substantially flat and directed toward the point of consumption, there being a space all about said baffle, the sectional area of which space is not less than that of the supply pipe.

In testimony whereof I affix my signature in presence of two witnesses.

ALEXANDER CONSTANTINE IONIDES, JR.
